UNITED STATES PATENT OFFICE.

ERNST G. K. ANDERSON, OF CHICAGO, ILLINOIS, ASSIGNOR TO ANDERSON ELECTRIC SPECIALTY CO., OF CHICAGO, ILLINOIS, A CORPORATION OF ILLINOIS.

SHADE-HOLDER.

1,245,855.

Specification of Letters Patent.

Patented Nov. 6, 1917.

Application filed April 15, 1916. Serial No. 91,292.

To all whom it may concern:

Be it known that I, ERNST G. K. ANDERSON, a citizen of the United States and a resident of Chicago, in the county of Cook and State of Illinois, have invented certain new and useful Improvements in Shade-Holders; and I do hereby declare that the following is a full, clear, and exact description thereof, reference being had to the accompanying drawings, and to the characters of reference marked thereon, which form a part of this specification.

This invention relates to improvements in shade holders for electric light fixtures, and refers more specifically to that type of shade holder which embraces in its construction a clamping device consisting of two or more open or loop-shaped clamping members which are adapted to fit over the large end of an electric light bulb and engage with said bulb in such manner that the shade supported thereby may be adjusted in various positions on the bulb so as to direct the light rays at varying angles.

My improvements relate more specifically to a shade holder of this character which is so constructed and arranged as to permit the clamping members of the holder to be folded or collapsed relatively to each other so as to enable said holders, or shades equipped with such holders, to be closely nested and therefore occupy compact space for the purposes of shipping and storage. Another object of the invention is to provide a construction of holder which may be made amply strong and reliable by the use of wire or other material substantially lighter than that heretofore used in shade holders of this general character.

The invention consists in the combination and arrangement of the parts shown in the drawings and described in the specifications and is pointed out in the appended claims.

I have shown in the drawings a number of modifications of my invention, certain of the embodiments being adapted to be attached to and form a unitary part of the shade, and others constituting separate fixtures which are adapted to be used with standard shades.

In the drawings:—

Figure 1 is a perspective view, as seen from beneath, of one form of shade holder and attached shade embodying my invention,

showing the manner in which it is used with an ordinary electric light bulb.

Fig. 2 is a similar view of the shade holder and shade with the holder folded or collapsed.

Fig. 3 is a sectional view of a plurality of holder-equipped shades showing the facility with which they may be nested.

Fig. 4 is a sectional view of another form of shade holder, as applied to a standard form of shade.

Fig. 5 is a perspective view of one of the holders, showing the holder members collapsed.

Fig. 6 is a vertical section of another form of holder, adapted for use in connection with beaded type shades.

Fig. 7 is a plan view showing the latter form of holder collapsed or folded.

Fig. 8 is a detail view illustrating the manner in which the hinged ends of the holder clamps are formed to facilitate folding, and which may be applied to either form of holders heretofore referred to.

Fig. 9 is a perspective view of a modified form of clamping member.

First referring to the construction shown in Figs. 1, 2 and 3, 10 designates a shade of common form, usually made of sheet metal. 11 designates an ordinary electric light bulb. 12, 12 designates the two members of a holder clamp which are fastened centrally to the top of the shade and within the same. Said clamping members 12 are preferably made of relatively light spring wire, and are of open or loop form, so that they may readily adapt themselves to the larger ends of electric light bulbs in such manner that the shade supported thereby may be practically universally adjusted about the longitudinal axis of the lamp so as to direct the light rays in all horizontal directions.

Heretofore it has been the common practice in making shade holders of this general type to rigidly fix the clamping members to the top of the shade. A disadvantage of the prior practice is that the clamping members extend practically to the lower rim of the shade so that the shade and holder necessarily occupy as much room, when packed for shipping or storage, as a solid semi-spherical body of the general dimensions of the shade.

In accordance with my invention, the two

2

clamping members constituting the holder are hingedly connected to the shade in such manner that they may swing toward and from each other. They may be thus attached to the shade through the medium of an attaching plate 14 which is fixed, as by means of a central rivet 15, to the shade in the axis thereof. The clamping members 12, as shown in Figs. 1, 2 and 3, are each made of a single piece of resilient wire with the end portions or arms 16, 16, next adjacent to the loop or ring-like parts of the clamping members, brought together and generally parallel with each other as herein shown. 10 Beyond said parts 16 the arms 17 of the clamping members are bent at an angle to the portions 16 and terminate in oppositely directed pintle portions 18 which, as herein shown, are hingedly connected to loops 19, 15 19 formed on the attaching plate 14, as best shown in Figs. 1, 2 and 8. Thus the clamping members are free to swing toward and from each other, and by reason of the resiliency of the wire constituting said members, one of the members may be passed 20 through the other when said members are swung toward each other so as to permit them to assume the folded position shown in Figs. 2, 3 and 8, substantially parallel 25 with the attaching plate 14. The folding or collapsing of the clamping members is facilitated by the angular arrangement of the portions 16 and 17 of the arms of the clamping members, as is best illustrated in 30 Fig. 8. Fig. 3 illustrates the facility with which a plurality of shades, equipped with the folding clamping members described, may be nested for shipment or storage. From an inspection of said figure, it will be 35 noted that the use of the foldable clamping members permits approximately four times 40 the number of shades to be nested or grouped in a given space as compared to the prior 45 form of shade having fixed clamping arms or members.

In Figs. 4 and 5 is shown a form of holder which is adapted to support on an upstanding electric light bulb a light cloth shade 25, sometimes reinforced by a reticulated metal 50 frame 26. This form of holder comprises a holder ring 27 of proper shape and size to fit snugly within the open truncated end of the shade. Said ring extends into the open end of the shade and is provided with a depending curtain-like flange 28 which engages the shade below the open end thereof and on which the shade is supported.

The clamping members 29, 29 of the holder are of open or loop-shaped form, as in the 60 construction previously described, to fit over the larger end of the lamp bulb. Each of said clamping members is shown as made of a single piece of wire and the ends 30, 30 are brought together in approximately 65 parallel relation and terminate in oppositely

directed pintles 31, 31 which engage in loops 32, 32 formed integral with or struck up from the ring 27. The said clamping members are adapted to be folded or collapsed one upon the other in the same general manner as in the construction before described, the folded positions of the parts being illustrated in Fig. 5. In this construction the supporting ring and the clamping members are furnished for use with standard shades 75 and are readily applied to the shades without the necessity of attaching means as in the previously described construction.

In Figs. 6 and 7 is illustrated a holder adapted for supporting a beaded type of shade 35 from an upstanding lamp bulb. This form of holder comprises a plate 36, which is fitted over the flanged upstanding portion 37 of the shade and is formed with a depending curtain-like flange 38 which encircles said portion 37. It is fastened to the shade in a familiar manner by screws 39 which extend through said flange 38 and engage under a bead 40 which surmounts the upstanding portion 37. The clamping 90 members 41, 41 are, in this instance, pivoted or hinged to an attaching plate 42 that is secured, as by means of a rivet 43, to the central portion of the holder plate 36. The ends of the wires constituting said clamping 95 members terminate in generally parallel angular portions 44, 45, respectively, the ends of which are directed oppositely to constitute the pintles 46 for engagement with hinge loops 47 of the attaching plate 42.

In all the construction described, it will be noted that the bulb-engaging loops of the clamping members are solid or continuous throughout their bulb-engaging portions so that thereby they may be made relatively light, while possessing sufficient resiliency to reliably support the same and the shade on the lamp bulb.

In Fig. 9 is shown a modification of the clamping member, which may be applied to either of the forms of holder before described, and is more especially applicable to the forms illustrated in Figs. 1 to 3, inclusive, and in Figs. 6 and 7. In the construction shown in said Fig. 9, the clamping member 48 is made of a single piece of wire, as in the constructions previously described, comprising two semi-loop portions 49, 49 and the angularly disposed arm portions 50, 51 at the hinged end of the clamping member. The arms 51, in this instance, are joined by an integral member 52 that constitutes the pintle of the clamping member, which is adapted to engage hinge loops of a supporting or attaching plate, like the plates 14 and 41, before described. The ends of the wire from which the clamping member is formed are brought close together on the side of the loop remote from the pintle. This arrangement gives considerable flexibility to the holder,

while at the same time the clamping member is sufficiently rigid to reliably clamp over and hold upon the lamp bulb.

I claim as my invention:—

- 5 1. A shade holder comprising looped resilient clamping members to engage over a lamp bulb and hinged to swing toward and from each other.
- 10 2. A shade holder for electric lamps comprising looped clamping members to engage over a lamp bulb and a mounting therefor to which the clamping members are hinged to swing toward and from each other to enable them to be folded or collapsed upon each other.
- 15 3. A shade holder for electric lamps comprising two clamping members, each made of a single piece of spring wire and comprising looped portions to engage over a lamp bulb; 20 pintle portions; and a support to which said pintle portions are hingedly connected, whereby said clamping members swing toward and from each other to enable them to be folded or collapsed upon each other.
- 25 4. A shade holder for electric lamps comprising a mounting for the shade, and

looped clamping members hinged to the mounting to swing toward and from each other and made of resilient material and of such dimensions, whereby one may pass 30 through the other to enable the members to be folded or collapsed upon each other.

5. A shade holder comprising two swinging clamping members each made of a single piece of wire embracing a centrally looped 35 portion and end pintle portions, with a mounting to which said pintle portions are hingedly connected.

6. In combination, a shade; an attaching plate fixed centrally within the shade, and 40 looped resilient clamping members hinged to the attaching plate to swing toward and from each other.

In testimony, that I claim the foregoing as my invention I affix my signature in the 45 presence of two witnesses, this 1st day of April, A. D. 1916.

ERNST G. K. ANDERSON.
